UNITED STATES PATENT OFFICE.

JOHN ADAM LANNERT AND EARL LEROY LANNERT, OF EAST CLEVELAND, OHIO.

SIGNALING-HORN.

1,177,420.

Specification of Letters Patent. Patented Mar. 28, 1916.

Application filed January 29, 1915. Serial No. 5,090.

To all whom it may concern:

Be it known that we, JOHN ADAM LANNERT and EARL LEROY LANNERT, both citizens of the United States, residing in East

5 Cleveland, in the county of Cuyahoga and State of Ohio, have jointly invented certain new and useful Improvements in Signaling-Horns, of which the following is a full, clear, and complete disclosure.

10 This invention relates to signaling horns, such as are adapted for use on automobiles or similar vehicles, and particularly to horns of the character above indicated in which the sound is produced by vibrating a dia- phragm by electro-magnetic mechanism.

15 The objects of this invention are to produce a horn or signaling device which is efficient, compact, and attractive; which can be produced at a low cost and is readily ad- justed.

20 Further objects of this invention will appear in the specifications and claims below.

Referring to the drawings forming a part of this specification in which the same reference characters are used to designate the 25 same parts throughout the various views, Figure 1 is a horizontal view looking at the front end of the complete horn; Fig. 2 is a longitudinal sectional view taken on the line 30 Y-Y of Fig. 1; Fig. 3 is a top plan view with the cover and amplifying member removed; Fig. 4 is a perspective view of the armature showing the impact fingers. Fig. 35 5 is a perspective view showing an alterna- tive method of applying the tension mem- ber; Fig. 6 is a side view showing another alternative method of arranging the tension member.

40 In the drawings, 1 represents a dished cover plate which may be the frame as shown. Resting on the flat portion of the dished cover plate is the diaphragm 2 which is made of an elastic material. In order to hold the diaphragm tight around its entire 45 circumference a ring 3 is placed thereon and screws passing through holes in the ring and diaphragm fasten the same securely to said dished cover plate. As will be later de- scribed, the screws 4, 5, and 6 also perform 50 other functions. Securely fastened to the diaphragm and near the center thereof is a tension member 7. This member has a head which engages at two diametrically opposite sides with the impact fingers 7^a on an armature 8, the latter being carried by a spring 8^a. A modification of this arrangement

would be to fasten the tension member to the armature.

The electromagnet assembly consists of a coil 9 wound upon or slipped over the core 10, the magnetic path being completed by the yoke 11 and the armature 8. The yoke 11 has two projections at its ends which project sidewise for the purpose of mounting the assembly and also to give the mag- 65 netic path a larger area at the air-gap. It will be noticed that the magnetic flux divides when entering the yoke, about one-half en- tering each side.

A contact spring 12 has a contact point 70 fastened at one end, which is normally pressed against the contact point on the armature 8. The contact spring 12 is thor-oughly insulated from the metallic parts by the two insulating blocks 13 and 14 and the 75 air space between the oversize hole in the contact spring 12 and the screw 4.

The screw 4 passes through holes in the projection of yoke 11, in the two insulating blocks 13 and 14, in the contact spring 12, 80 in one of the holes of the ring 3 and dia- phragm 2 and is screwed into the dished cover plate 1, thus fastening these mem- bers rigidly together. The screw 3 passes through holes in the other projection of 85 yoke 11, in the metallic spacing block 15, in the pivot spring 8^a for the armature 8, in the spacing block 16 (shown of an insulating material to perform another function), and one of the holes of the ring 3 and diaphragm 90 2 and is screwed into the dished cover plate 1, thus rigidly fastening these members to- 95 gether in operative relation to each other.

The cover 17 and amplifying member 18 are fastened together and the assembled unit 95 is held in place by the perforated disk 19 normally deflected by the screw 20, thus holding these members securely to the body of the horn and allowing them to be easily removed for inspection.

100 Assuming the flexible lead wire 21 to be connected to the positive terminal of the electrical source, the electrical circuit will be to the binding screw 22 where connection is made with one of the ends of coil 9. The 105 other end of coil 9 is connected to the insulated contact spring by soldering to a small projection thereon or by any other convenient method. The contact spring 12 and the armature 8 are normally in connec- 110 tion with each other. The circuit from the armature to the connection with the lead

wire 23 under the binding screw 6 is through the metallic parts of the horn. Obviously, when a current is passed through the coil 9 a magnetic flux will be set up and thus attract the armature. The impact fingers 7^a on the armature 8 may normally rest against the head of the tension member 7 or may be a short distance away, the effect being a difference in the loudness of the sound. When the impact fingers are in contact with the head of the tension member 7 a further movement of the armature whether caused by magnetic attraction or inertia will deflect the diaphragm. An insulated adjusting stop screw 24 is so set that the electric current will be interrupted and the armature will then be returned by the force of the deflected diaphragm and the armature pivot spring. When the armature returns to its original position the contacts close the circuit thus causing the magnet to attract the armature again. This operation takes place with great frequency so that the successive deflections of the diaphragm vibrate the surrounding air with sufficient frequency to produce a loud sound. The sound passes through the amplifying member 18 and emits from the perforations in the disk 19.

Having thus described our invention, what we claim is:

1. In a signaling horn, the combination with a frame plate and a horn coöperating therewith to form an amplifying chamber, of a diaphragm secured to said frame plate, a yoke disposed within the amplifying chamber and spaced forwardly from said diaphragm, means for securing said yoke in place, a magnet supported in said yoke, an

armature for said magnet in front of the diaphragm, circuit breaking means also in front of the diaphragm and coöperating with said armature, and connections between said armature and the diaphragm.

2. In a signaling horn, the combination with a dished frame plate, and a horn forming an amplifying chamber, of a yoke located in said amplifying chamber and spaced forwardly from said dished frame plate, a diaphragm between the frame plate and yoke, a magnet supported by said yoke, devices between the diaphragm and magnet and coöperating with the latter to form a rheotome, and connections between said devices and the diaphragm.

3. In a signaling horn, the combination with a dished frame plate, and a horn structure forming an amplifying chamber, of a yoke located within said chamber forwardly from the frame plate, said yoke having lateral extensions spaced from and secured to the frame plate, a magnet carried by said yoke, means securing said yoke extensions to the frame plate, a diaphragm secured to the frame plate, an armature supported between said diaphragm and magnet, circuit breaking means coöperating with said armature, and a tension device connecting the diaphragm with said armature.

In testimony whereof, we hereunto affix our signatures in the presence of two witnesses.

JOHN ADAM LANNERT.
EARL LEROY LANNERT.
